UNITED STATES PATENT OFFICE.

HERMAN H. KORTHAUER, OF BENSENVILLE, ILLINOIS.

ATTACHMENT FOR STOVES OR FURNACES.

SPECIFICATION forming part of Letters Patent No. 640,778, dated January 9, 1900.

Application filed April 29, 1899. Serial No. 715,024. (No model.)

To all whom it may concern:

Be it known that I, HERMAN H. KORTHAUER, a citizen of the United States, residing at Ben-
serville, in the county of Du Page and State of
Illinois, have invented certain new and useful
Improvements in Attachments for Stoves or
Furnaces; and I do hereby declare the follow-
ing to be a full, clear, and exact description
of the invention, such as will enable others
skilled in the art to which it appertains to make
and use the same.

My invention relates to stoves and furnaces;
and it consists in certain novel features of con-
struction and combination of parts, the pre-
ferred embodiment or materialization of
which will be hereinafter fully described, and
illustrated in the accompanying drawings,
made a part of this application.

The object of my invention is to more effect-
ively utilize the heat within a stove or fur-
nace than is now common. This result I ac-
complish by practically increasing the radiat-
ing-surface presented to the action or in-
fluence of the fire, which I accomplish in a
very simple, cheap, though thoroughly effi-
cient manner.

A further object attained by the use of my
invention is the utilization or taking up of the
lower and colder strata of air and passing it
through or over heated surfaces, and thereby
raising the temperature thereof to an agree-
able point, thus insuring a complete circula-
tion of air in a room and that the air nearest
the floor will be practically of the same tem-
perature as that nearest the ceiling.

While I have illustrated and shall describe
in the following specification the preferred
construction and arrangement of parts, it will
be understood that I desire to comprehend the
substantial equivalent thereof, and I do not
therefore wish to be confined strictly to the
exact showing I have made.

In the accompanying drawings, Figure 1 is a
vertical section of an ordinary heating-stove
provided with my air-heating attachment.
Fig. 2 is a top plan view of the attachment
removed. Fig. 3 is a perspective view of an
ordinary cooking stove or range, showing my
attachment in the position usually occupied
by a water-heating boiler. Fig. 4 is a longi-
tudinal section of my attachment and the top
of a stove, showing the relative position of

said parts to each other when in their coöp-
erative positions.

In order to conveniently refer to the several
parts of my invention and such coöperating
features as may be necessary to illustrate the
use thereof, designating-numerals will be em-
ployed, of which 1 indicates the body-section
or fire-pot of an ordinary stove having the
usual upper portion or magazine extension 2,
the fuel-door 3, and the flue connection 4, all
of said parts being substantially of the usual
construction.

Within the magazine portion or extension 5
I mount and removably secure my improved
air-heating attachment, which consists of the
exterior body or cylinder 5 and the interior
cylinder 6, both of said parts being prefer-
ably cylindrical, though other form of outline
may be adopted, it being understood that the
interior tube or cylinder 6 is of considerably
less diameter than the outer casing or cylin-
der 5.

Fitting tightly around or permanently se-
cured to the lower end of the inner casing or
tube 6, which is left permanently open at its
lower end, is the collar 7, which extends out-
ward and is permanently attached to the
lower edge of the outer casing 5, thereby in-
closing and supporting the inner tube. Im-
mediately above the collar 7 I secure to the
inner walls of the outer casing 5 and to the
outer walls of the inner casing 6 the perfo-
rated collar or air-commingling plate 8, and
connecting with the annular chamber 9 thus
provided between the collar 7 and the plate
8 is the air-delivering pipe or tube 10, which
extends outward through a suitable aperture
provided in the wall of the stove and thence
downward to a point near the floor. In Fig.
1 it will be seen that this pipe is shown as
extending out of the body portion of the
stove and thence downward at right angles,
though it is thought that a preferable and
more sightly construction would perhaps dis-
pose said tube more closely against the ex-
terior wall of the stove.

The upper edge of the exterior casing 5 may
be provided with a continuous flange or with
anchoring-ears 11, by means of which the de-
vice may be secured in position by stove-bolts
12, passing through the top of the stove and
properly secured by nuts in the usual way.

The inner casing or tube 6 may be employed as the throat of a magazine, through which coal may be introduced to the fire in the usual manner, in which case the lid or cap 13 should 5 be removably secured upon the upper end of said tube and provided with a suitable handle, (not shown,) whereby said lid or cap may be readily removed and replaced; but it is thought that better results would be reached 10 by introducing the fuel through a suitable opening, as the door 3.

It will be observed that since the interior casing 6 is of much less diameter than the outer casing 5 there will be an annular chamber or space 14 around said inner casing, which I utilize to locate the spirally-arranged plates 15, which are multiplied in number according to the size of the flues to be formed. By the arrangement illustrated in Fig. 2 it 15 will be observed that between said plates will be formed a continuous spirally-disposed flue or opening 16, affording a greatly-extended line of travel for the air received through the tube 10. By suspending my air-heating device within the body of the stove immediately over or under the influence of the fire the flame and heat will not only wrap around the exterior casing 5, but will also extend freely upward through the open end of the inner 20 casing 6, and in order to prevent a dead-air chamber from being formed within the inner casing I provide the laterally-extending duct 17, designed for the escape of accumulated gases, smoke, &c., thereby insuring a more 25 perfect circulation of heat and an incident increase in temperature of the air passing upward through the spiral flue 16 and thence upward through an opening provided in the usual cap or hood 18 of the stove.

By the arrangement of the parts which I have just described and illustrated the hot air within the stove is more effectively utilized than would be possible without such means, inasmuch as the only radiation of heat 40 from a stove as now constructed takes place from the exterior surface thereof, the interior air, though of highest temperature, being permitted to escape through the chimney without delivering its just portion of caloric. 45 The advantage resulting from forming the flues spirally will at once be appreciated, inasmuch as flues of great length may be disposed within the upper portion of a stove without the necessity of so extending or increasing the length of the exterior casing surrounding said flues as to in any way prevent ready accessibility to the fire-pot or obstruct the action of the flame, it being obvious that 50 the length of the flues is determined by the 55 degree of spirality of the plates 15.

It is found in practice that since the exterior walls of the flues are heated to a high degree the air will move rapidly upward through the same, and the draft thus induced will 60 cause the cold air near the floor to be taken up and rapidly passed through said flues, thereby utilizing to the fullest extent the in-

terior heat of the stove, which would otherwise impotently pass into the chimney, the result being great wastefulness of the utilization of the fuel. 70

It is now common to extend the flue or pipe of the stove through the ceiling of the room in which the stove is located and thence upward through the floor of the room above, 75 when a drum is attached to said pipe and connection made with the drum and the chimney, the result being an unsightly and cumbersome device. By the use of my air-heating appliance the cumbersome drum and obstructing pipe may be entirely dispensed with and in lieu thereof a neat tube, of tin or the like, 80 may be arranged to extend upward from the opening in the hood 18 through the ceiling and into a register provided in the floor of the 85 room above, thus insuring that said room will be thoroughly though economically heated.

I am aware that it is common to arrange spirally-disposed flues for the purpose of conducting the smoke, heat, and other products 90 of combustion over or in contact with the maximum amount of radiating-surface; but this plan is very objectionable and unsatisfactory, inasmuch as soot, ashes, and the like will so greatly accumulate that the heat will 95 have little effect upon the surface intended to be heated, but will pass into the chimney without much benefit to the room in which the stove is located.

While I have illustrated my air-heating appliance as used in connection with an ordinary heating-stove in which coal is employed as fuel, it will be understood that it will be desirable for use upon any variety of stove or furnace and, in fact, will be especially desirable as a furnace attachment, in which case the number of devices, each having spirally-disposed flues, should be multiplied according to the size of the furnace above the fire-pot, it being clear that a half-dozen of such devices, more or less, as illustrated in Fig. 2, could be disposed adjacent to each other within the upper portion of a furnace-body and there secured in any suitable way, as by arms or brackets secured to the interior surface of the furnace-wall, each of the interior tubes of each device being properly ventilated with a suitable duct corresponding to the duct 17. Where a number of air-heating devices are thus grouped together in a furnace-body, it 110 will be desirable to provide a dome at the top of the furnace, which will be a common delivery-point for all of the devices grouped together below, and it is obvious that by providing said dome with a number of apertures 115 the heat therein could be readily delivered to all of the rooms of a building, and since the air passes with considerable velocity through the spiral flues, owing to the intense heat to which it is subjected, the air is actually forced 120 through the delivery-pipes into another part of the building, even against the direction of the prevailing wind, which is not possible 125 with furnaces as now constructed.

I prefer to deliver the cold air as it comes through the pipe 10 into the annular chamber 9 instead of passing it directly into the flues, since the air will be temporarily held in check within said chamber, and thereby initially heated before passing upward, thereby being evenly distributed through the apertures provided in the plate 8, thus insuring that each of the flues will receive its proper quota of air and that the cold air cannot immediately and rapidly leave the flues without being raised to the proper temperature, and, furthermore, by holding the cold air in check within the annular chamber 9 the bottom of the device is prevented from becoming warped or rapidly burned out and ruined.

In addition to the great advantages arising as a result in the use of my improved air-heating apparatus as applied to heating stoves and furnaces it will also be found to be very desirable and important, with slight modifications in the construction thereof, for use upon cooking-stoves, as illustrated in Figs. 3 and 4, since a cooking-stove, as a rule, is designed only with reference to its cooking capacity, and as a result the average kitchen is not well heated, especially near the floor, and it is obvious that by the use of my invention the cold air may be drawn upward through the pipe 19, which corresponds to the pipe 10 in Fig. 2, and thence taken under a perforated diaphragm or collar corresponding to the collar 8, and thence fed upward through such perforations into a series of flues 20, which are increased in number, as desired.

In adapting my air-heating device for use upon cooking-stoves I prefer to provide an exterior casing 21 of elongated or oval form corresponding somewhat in outward appearance to an ordinary washboiler, it being understood that the interior casing 22, corresponding to the interior casing or tube 6, is of corresponding shape with the said exterior casing, thereby providing a continuous annular chamber between the outer casing 21 and the inner casing 22, in which I dispose the spirally-arranged plates or flanges 23, corresponding in function or office with the plates 15 in Fig. 2. To the upper edge of the casing 21, which corresponds to the exterior casing 5 in Fig. 2, I attach or integrally form therewith the housing or shell 24, which is inclined outward at its lower end and is designed to fit within the usual opening of a stove after the lids and X-pieces have been removed or may be of sufficient extent to entirely cover said opening, and thereby prevent the escape of gas or smoke. By this arrangement it will be seen that I form around the exterior casing proper, 21, and said outer shell or housing 24 an annular chamber 25, up into which the heat and flame may extend, thereby enabling the heat to reach upon the outer sides of the flues, while the inner sides of said flues are also affected by the flame and heat as it extends upward in the tube or casing 22, it being understood that the permanently-secured

cap 26 is attached to the upper end of said inner casing.

By the construction which I have just described and which is fully illustrated in Figs. 3 and 4 it will be appreciated that I have provided a simple attachment which may be readily applied to use upon a cooking-stove and as promptly removed therefrom when not in use, thereby insuring that the cold air nearest the floor will be taken up and heated and the temperature of the room thereby rendered more agreeable. It will be readily appreciated that various modifications may be made by means of which my air-heating device will be rendered applicable to almost any stove or arranged to fit upon almost any variety of stove, furnace, or other source of heat and that it may be made a permanent part of the stove or furnace or manufactured as a simple article complete within itself and ready to be placed over the source of heat.

My invention may be readily formed of any metal suitable for the purpose and may be built up of several separate pieces of sheet metal, or most of the parts thereof may be cast or integrally formed in one piece, thereby making it possible that the cost of manufacture may be reduced to a minimum point.

It is clear that various simple modifications of the means I have herein described and illustrated may be employed by which the heat may be conveyed to any or all of the rooms in a building from a simple heating-stove of ordinary construction—as, for instance, by providing a drum adapted to fit over the top of the stove into which the heat from the flues is delivered and thence conveyed by suitable pipe connections to the points where it is desired to use the same.

By disposing my heating appliance within the body of the stove the direct effect of the heat comes in contact with the sides of the flues, thereby greatly increasing the surface of radiation, and since no soot, ashes, or other products of combustion can collect upon any of the parts of my heating appliance use does not effect the efficiency thereof.

By increasing the number and length of the flues the air is confined within a smaller space and will be heated more quickly and raised to a much higher degree of temperature than if the flues were larger, and even though the flues are of great length and of slight pitch or upward inclination the high degree of temperature to which the air is raised will insure that there will be a vigorous or rapid draft through the same and that when the air is released at the top of the stove it will be much more perfectly heated than if passed more directly through the stove, as would be the case if the flues were of larger extent and more rapid pitch.

It is thought that the advantages enumerated and others will be fully appreciated and understood from the foregoing specification, and believing that the construction has been made entirely clear I will now set forth what

I claim as new and desire to secure by Letters Patent.

1. As an attachment for stoves, furnaces, or the like, air-heating flues spirally disposed around an inner casing open at its lower end and closed at its top; an exterior casing enclosing said flues; a collar connecting the lower open end of the inner tube and the lower end of the exterior tube; a perforated flange or disk fitting around said inner tube and located above said collar whereby a cold-air-receiving chamber will be formed below said flues and means to deliver the cold air in said chamber, as specified and for the purpose set forth.

2. As an improvement in air-heating appliances for furnaces, stoves, the herein-described device consisting of an inner and outer shell or casing, the former being closed at the top and open at the bottom; a flange extending from the open end of said inner casing to the lower end of the outer casing; a perforated partition secured to the exterior wall of the inner casing and the interior wall of the outer casing and located above said flange; spirally-disposed plates extending around the inner casing and occupying the annular chamber between said casings; means to secure the outer casing in place and a pipe extending from the chamber below said perforated partition outside of the stove to a point near the floor whereby the cold air will be gathered and delivered through the spiral flues provided by said plates in the manner specified and for the purpose set forth.

3. As an improvement in air-heating appliances for furnaces, stoves, the combination with a stove-body, of a spirally-arranged flue disposed within the body of the stove or furnace immediately above the fire-pot; suitable casings designed to inclose said flues whereby the flame and heat may pass upon both sides thereof, and an air-pipe extending from a

point near the floor upward into the stove in communication with said flues, and a perforated disk adapted to temporarily check the cold air before entering the flues, whereby said air will be evenly distributed in the manner specified and for the purpose set forth.

4. As a new article of manufacture, the herein-described air-heating device consisting of an outer and inner casing, the latter open only at the bottom and the former open only at the top; a perforated flange or disk separating the annular chamber formed between said casings into two compartments; a spirally-arranged plate or plates secured to the exterior wall of the inner casing and the interior wall of the exterior casing, whereby an inclined flue or flues may be formed within said annular chamber; a duct or tube extending from the closed upper end of the inner tube outward through the spirally-disposed flues and exterior casing, and a pipe communicating with the compartment below said perforated collar and extending to a point near the floor, all combined as specified and for the purpose set forth.

5. An air-heating appliance, consisting of a pair of shells or casings, one fitting within the other and thereby forming an annular chamber closed at the bottom and open at the top; a tightly-fitting cap for the upper end of the inner chamber; spirally-disposed flanges or plates disposed in said annular chamber; a perforated flange or plate located below said flues, whereby the cold air as received will be evenly distributed to the flues and means to hold said device in an adjusted position, as specified and for the purpose set forth.

In testimony whereof I affix my signature in presence of two witnesses.

HERMAN H. KORTHAUER.
